CENTRIFUGAL CASTING APPARATUS

Louis A. Camerota, Burlington, N. J., assignor
to Walter Wood, Philadelphia, Pa.Application September 19, 1932
Serial No. 633,704

8 Claims. (Cl. 22—65)

This invention relates to the art of making hollow metal bodies by centrifugal casting, and more particularly to apparatus for centrifugally casting iron pipe or like articles, such apparatus including a plurality of casting machines which are movable over a predetermined course from one foundry station to another, and which perform certain flask handling functions in addition to their primary function of centrifugally casting metal bodies within the flasks.

Heretofore it has been customary practice in this art to employ stationary casting machines, and to convey flasks to and from the machines. With such practice the casting operation at each machine consumes a considerable period of time. When a flask is in readiness for the casting operation it is brought to an idle machine, placed thereon, and caused to rotate at a slow speed. The charge of molten metal is then poured into the flask, and the speed of rotation is accelerated. Subsequently, when the casting has been formed, the speed of rotation is decelerated gradually. From the time that the mold has been fully charged until the casting operation has been completed, and the flask has come to a full stop, there is a considerable interval during which the machine is not available for other work. Moreover, where a battery of stationary casting machines is used, flasks must be conveyed to and from the different machines, and ladles of molten metal must be carried from one location to another. Accordingly it will be seen that with one or more stationary centrifugal casting machines there are many factors which interfere with rapid production and which complicate the handling of the flasks and the operation of charging the molds.

The principal object of my invention is to obviate the aforementioned difficulties and to increase the speed of production in making centrifugally cast metal bodies, while simplifying the handling operations normally involved in such manufacture. This end I accomplish by employing a number of casting units which are movable independently or in groups, according to a predetermined plan, from one foundry station to another, and the operation of which is rendered for the most part automatic and made a part of the complete foundry system, so that the foundry system becomes in effect a single machine capable of continuous operation.

Other specific objects and advantages characteristic of my invention will become more fully apparent from the description hereinafter of one example or embodiment thereof, the descrip-

tion having reference to the accompanying drawings. Of the drawings:

Fig. I represents a plan view of the complete apparatus embodying my invention.

Fig. II represents a cross section of the same taken at the transfer station as indicated by the lines II—II of Fig. I.

Fig. III represents a cross section of the same taken at the pouring station as indicated by the lines III—III of Fig. I.

Fig. IV represents a cross section of the same taken at the flask receiving station as indicated by the lines IV—IV of Fig. I; and

Fig. V represents a cross section of the same taken at the flask discharging station as indicated by the lines V—V of Fig. I.

In the drawings there is shown an embodiment of my invention in which the apparatus is designed for the manufacture of cast iron pipe in flasks lined with refractory molds. The flasks, designated at 1, with their molds prepared, are initially conveyed to a trackway which I conveniently term the "flask receiving station", which is comprehensively designated at 2, and which comprises in the present instance an elevated table made of parallel rails 3. From the flask receiving station 2 the flasks 1 are transported in pairs onto movable casting machines 4. The casting machines 4 are progressed in the direction represented by the arrows in Fig. I along a predetermined course constituting a closed circuit.

During this progression each machine is momentarily halted at a pouring station, comprehensively designated at 5, where molten metal is charged into the flasks. After completing the circuit each machine 4 is momentarily halted at a station 6 in the form of a trackway which I conveniently term the "flask discharging station", and at which the flasks with the pipe castings therein are discharged for further progression to a mold disintegration station where the flasks are stripped of their castings.

The circuit over which the centrifugal casting machines 4 travel comprises a set of tracks 7, 8, 9, and 10 disposed in the form of a rectangle. One track 7, constituting one side of the rectangular circuit, leads from the flask receiving station 2 to a point beyond the pouring station 5. Another track 9, constituting the other side of the circuit, leads to the flask discharging station 6. The tracks 8 and 10, constituting the ends of the circuit, are disposed in a plane below that of the tracks 7 and 9. By means of transfer cars 11a and 11b, movable back and forth on the tracks 8 and 10 respectively, the casting machines

100
105
110

4 are shifted across the ends of the circuit from one side track to the other.

Each casting machine 4 comprises a carriage 12 having bearings in the form of rollers 13, 13a which rotatably support a pair of flasks 1, and a prime mover 14, preferably an electric motor, for driving the flasks. As clearly shown in Fig. II, the motor 14 is connected through gearing 15 to a drive shaft 16. The drive shaft 16 is in turn connected through gearing 17 to the center rollers 13a which serve as the driving elements for rotating the flasks. The carriage 12 of each casting machine 4 is stepped down at one end 18 to provide a depressed support for the motor 14, and the flasks 1 are caused to project beyond the other end of the carriage to facilitate the operation of charging their molds with molten metal. At each side of the carriage 12 there are smooth flat faces 19 which afford striking abutments through which the movement of one carriage is imparted to the carriage of the next adjacent machine. On the top of the carriage 12 there are provided two projecting members 20 having inclined cam surfaces 21 which, as hereinafter described, are useful in connection with the discharge of flasks from the machine. Beneath the carriage 12 there are flanged wheels 22 which engage the tracks 7 and 9 and which are disposed transversely to the axes of the flasks 1.

30 The casting machines 4 are adapted to be moved simultaneously as to groups in the direction indicated by the arrows in Fig. I. For progressing the casting machines 4 along the track 7 there is a pressure cylinder 23, located at the flask receiving station 2, the plunger 24 of which is adapted to strike the side of one machine and to move it onto the track 7, while concurrently advancing the entire group of machines on the track 7 one step away from the flask receiving station 2. Similarly for progressing the casting machines 4 along the track 9 there is a like pressure cylinder 25 having a plunger 26 which when operated moves the entire group of machines on the track 9 one step toward the flask discharging station 6.

For the purpose of transferring the casting machines 4 from one side track 7, 9 to the other, the transfer cars 11a, 11b have short rail sections 27 disposed across their platforms. As shown clearly in Fig. IV, the rail sections 27 of the transfer cars 11a, 11b are normally in registry with the tracks 7 and 9. Accordingly the transfer cars 11a, 11b are adapted, when positioned at the end of a side track 7 or 9, to receive a casting machine 4 as the group of machines is advanced by operation of the pressure cylinder 23 or 25. The transfer cars 11a, 11b are equipped with flanged wheels 28 which engage the tracks 8, 10.

The means employed for shifting a transfer car 11a, 11b along its track 8, 10 comprise, in the present example of my invention, pressure cylinders 29a and 29b, and counterweights 30a and 30b respectively, there being one such cylinder and counterweight for each track 8, 10. The operation of the transfer car will be understood from examination of Fig. II of the drawings. When pressure is admitted to the cylinder 29a its piston 31 is raised. The piston 31 carries a sheave 32 which engages a wire cable 33 one end of which is made fast at 34 and the other end of which is attached to the transfer car 11a. An additional sheave 35 guides the cable and maintains it parallel to the track 8. Movement of the piston 31 in an obvious manner causes the transfer car to be advanced from the position

shown in full lines in Fig. II to the position shown in broken lines. Opposite to the pressure cylinder 29a there is a counterweight stand 36 provided with a series of sheaves 37, 38, and 39 which engage a wire cable 40, one end of which is attached to the transfer car 11a and the other end of which is attached to the counterweight 30a in the pit 41. In an obvious manner when pressure is released in the cylinder 29a the transfer car 11a will be returned from the position shown in broken lines to the position shown in full lines. The operation of the transfer car 11b is accomplished in an identical manner.

The elements of the pouring station 5 are shown most clearly in Fig. III. They comprise two cupolas 45 having stationary gates 46 which lead to a pivoted gate 47. The pivoted gate 47 may be turned from one position to another to empty alternatively into either of two ladles 48. From the ladles 48, which serve as measuring ladles, 95 metal is poured into pouring spouts 49, and from thence it enters the projecting ends of the flasks 1 mounted on the casting machine 4 which is positioned at the pouring station. When charging the flasks the pivoted gate 47 is first swung to one 100 position, which causes the molten metal from the cupola 45 to enter one measuring ladle 48 and its corresponding flask 1. The pivotal gate 47 is then swung to the other position, charging metal into the other measuring ladle 48 and its 105 corresponding flask 1.

In Fig. IV there is shown in detail the elements of the flask receiving station 2. Flasks with their refractory molds prepared for the casting operation are rolled to the flask receiving station 110 along the trackway comprising the parallel rails 3. For guiding the flasks two such rails 3 at one side are spaced apart to accommodate annular flanges 50 located at one end of each flask. The rails 3 terminate in an elevated flask support 51. 115 The elevated support 51 conveniently takes the form of a forked arm pivoted at 52 and having a portion 53 which is connected by a link 54 with the piston rod 55 of a pressure cylinder 56. The forked arm 51 is preferably provided with a pair 120 of notches 57 at its outer end which serve to accommodate a pair of flasks in spaced relation. Similar notches 58 are provided near the ends of the rails 3 for limiting the position of the flasks as they are lined up on the rails in preparation 125 for the casting operation. The operation of the pressure cylinder 56, which serves to raise and lower the forked arm 51 is governed by a control valve 59, the latter being in turn controlled by an operating lever 60. A spring 61 connected 130 to the operating lever 60 maintains the control valve 59 normally closed.

When the transfer car 11b carrying thereon a casting machine 4 is shifted along the track 10 to the flask receiving station 2 the transfer car 11b and the machine thereon are brought to a position directly beneath the forked arm 51 which in that situation extends horizontally as shown in Fig. IV. Preparatory to the movement of the transfer car 11b a pair of flasks are rolled out 140 to the notches 57 at the ends of the forked arm 51. As the transfer car comes to the flask receiving station 2 its casting machine 4 strikes the operating lever 60 of the control valve 59. This causes pressure to be admitted in the pressure 145 cylinder 56 raising its piston 55 and lowering the forked arm 51 above its pivot 52. The lowering of the forked arm 51 automatically deposits the pair of flasks at the end of the arm onto the bearings 13, 13a of the casting machine 4. When 150

the casting machine 4 is progressed by operation of the plunger 24 of the pressure cylinder 23 forward along the rails 7 toward the pouring station 5 the spring 61 causes a return of the operating lever 60 to its original position which exhausts the pressure cylinder 56 and causes the forked arm 51 to return to its original horizontal position. It will thus be apparent that the deposit of flasks on the casting machines 4 is effected 10 automatically incident to the movement of the casting machines to the flask receiving station.

In Fig. V there is shown in detail the elements of the flask discharging station 6. These elements comprise an elevated flask support 62 having pivoted thereto a discharge skid 63. The skid 63 comprises two sections 64 and 65 joining each other at an obtuse angle, each section comprising a pair of arms. Disposed near the end of the section 65 of the pivoted skid 63 there is 15 a flask conveyor 66 which in the selected example comprises reciprocatory skids 67a and 67b which are adapted to be alternately raised and lowered by means of a rocker arm 68, while guided in their movement by guide rollers 69. The particular form of conveyor of which a portion is 20 illustrated in Fig. V is more fully described in my pending application for U. S. Letters Patent Serial No. 586,316, filed January 13, 1932.

When a casting machine 4 is advanced by 25 means of the plunger 26 of the pressure cylinder 25 along the track 9 toward the flask receiving station 6, the arms of the section 64 of the pivoted skid 63 are caused to extend between the carriage 12 of the casting machine and the flasks 30 thereon. Moreover, these arms are engaged by the cam surfaces 21 of the casting machines, so that, as each machine approaches the flask discharging station, the arms are caused to pick up the pair of flasks on the machine and to roll 35 these flasks by gravity to the position shown in Fig. V. Notches 70 in the rails 71 leading from the flask discharging station determine the ultimate position to which the flasks are rolled when discharged from a casting machine; and it will 40 be particularly noted that one flask remaining on the arms of the section 65 of the pivoted skid 63 causes by virtue of its weight the arms of the other section to be maintained in elevated position until the flask conveyor 66 effects a further 45 progression of the flasks away from the flask discharging station. When the flask conveyor 66 is operated, the elevation of the reciprocatory skid 67a progresses the flask from the notches 70 forward along the rails 71 by a rolling movement. 50 Subsequently, when the skid 67b is operated, the other flask of the pair will be similarly progressed onto the notches 70. When the conveyor has 55 operated to this point the pivoted discharge skids 63 are relieved of the weight of the flasks and are caused to return to the position shown in broken lines in Fig. V. The conveyor 66 leads to a mold disintegrating station whereat the flasks 60 are stripped of their castings, but this station forms no part of the present invention and is not therefore illustrated in the drawings.

It will be observed that the pivoted skid 63 at the flask discharging station 6 must not be lowered until the casting machine has been transferred across to the flask receiving station 70 2, for otherwise the pivoted skid 63 would strike the flask supporting bearings 13 of the casting machine. However, provision is made for automatically causing the movement of the transfer car from the flask discharging station 6 to the flask receiving station 2 before the pivoted skid

63 is lowered by movement of the flasks from off the ends of the skid. When a casting machine is moved to the flask discharging station 6 it strikes an operating lever 75 of a control valve 78 which causes the pressure medium to be admitted to the pressure cylinder 29b which operates the transfer car 11b. Accordingly the shift of the transfer car 11b takes place before a double stroke of the conveyor 66 has occurred. By the time the flasks have been moved away from the flask discharging station 6 on the conveyor 66, and the pivoted skid 63 has returned to its lowered position, the transfer car 11b has carried its empty casting machine on to the flask receiving station 2.

The means for controlling the several functions of the above described apparatus are shown diagrammatically in Fig. I. The main pressure line is represented at 80 and has one branch 81 which leads to the transfer control valve 78 which governs the shifting of the transfer car 11b from the mold discharging station 6 to the mold receiving station 2. Another branch 82 from the main pressure line 80 leads to a similar transfer control valve 83 which controls the shifting of the transfer car 11a. The transfer control valves 78 and 83 are interconnected by a rod 84, and they are so arranged that when one valve is opened the other valve is closed and vice versa. The connecting rod 84 is actuated by a bell crank lever 85. The bell crank lever 85 is fulcrumed at 86 and is moved in one direction by movement of the operating lever 75, previously referred to, and is moved in the other direction by means of an additional operating lever 87 fulcrumed at 88, the latter lever being actuated by movement of the casting machines 4 from the mold receiving station 2 toward the pouring station 5. From the transfer control valve 78 there is a pressure line 89 which leads to the pressure cylinder 29b. Likewise from the transfer control valve 83 there is a pressure line 90 which leads to the pressure cylinder 29a.

The main pressure line 80 also has a branch 91 which leads to the control valve 59, previously referred to which governs the operation of the pivoted arms 51 at the flask receiving station 2. The main pressure line 80 leads to a valve 92 which I conveniently term the "master control valves". From the master control valve 92 there 125 is a line 93 leading to the pressure cylinder 23 which causes movement of the casting machines 4 from the mold receiving station 2 toward the pouring station 5.

An additional branch 94 from the main pressure line leads to a control valve 95 governing operation of the pressure cylinder 25. As the transfer car 11a moves from the side track 7 to the side track 9, it strikes an operating lever 96 which opens the control valve 95 and causes a movement of the plunger 26 of the pressure cylinder 25. With return of the transfer car 11a to its original position a spring 97 returns the operating lever 96 to its normal position closing the valve 95. The various control valves hereinbefore mentioned are each provided with exhaust lines designated at x.

For convenience of illustration the several successive spaces of the circuit over which the casting machines 4 travel are designated by the letters A to N in the order in which the casting machines travel. At the space designated at A the casting machine receives a pair of flasks. At the space designated at B the refractory linings of the flasks are preferably dried by means of a

blow torch. At the space designated at C the head cores are placed in the ends of the flasks. At the space designated at D, which corresponds to the pouring station, molten metal is charged 5 into the flasks. As a casting machine passes from space C to space D current collecting brushes 98, shown in Fig. III at the base of the carriage 4, engage wires 99 and automatically start the operation of the motor 14 of the casting 10 machine, so that by the time the machine has reached the pouring station the flasks are rotating.

At the spaces designated at E and F the flasks are turning and the centrifugal casting operation 15 is being completed. At the space designated at G the casting machine moves off the side track 7 onto the transfer car 11a. As the casting machine 4 moves from space F to space G the current collecting brushes 98 move out of contact 20 with the wires 99; which extend from y to z, thus causing the speed of rotation of the flasks to decelerate. At the space designated at H the flasks are still turning and in the customary operation they continue to turn through space I, 25 J, and K. At the spaces designated at L and M the flasks have ceased to turn, and the castings therein are cooling. At the final space designated at N the flasks are discharged from the casting machines onto the conveyor 66. Obviously 30 the various steps involved in the movement of the casting machines may be varied considerably and need not follow the particular example herein outlined.

The operation of the above described apparatus 35 is as follows: Assuming that the various elements of the apparatus are all in the position shown in Fig. I, it will be observed that one casting machine has just reached the space N, that its flasks have been discharged, with one flask remaining on the 40 pivoted skid 63 which is in elevated position, and that the operating lever 75 of the transfer control valve 78 has been moved to a position which has caused the transfer control valve 78 to be opened and the transfer control valve 83 to be 45 closed. With the parts in this position the pressure medium is cut off from the pressure cylinder 29a which operates the transfer car 11a, and accordingly under the influence of the counterweight 30a the transfer car 11a is automatically 50 returned to a position in registry with the tracks 7. Return movement of the transfer car 11a automatically cuts off the pressure medium from the pressure cylinder 25, under influence of the spring 97 on the operating lever 96, which causes 55 a retraction of the plunger 26. Moreover, the transfer control valve 78 being opened, the pressure medium is admitted to the pressure cylinder 29b causing the transfer car 11b to be shifted from space N to space A, carrying thereon a casting 60 machine 4 the flasks of which have been discharged onto the pivoted skid 63. As the transfer car 11b carrying its empty casting machine approaches the flask receiving station 2, its casting machine strikes the operating lever 60, opening 65 the control valve 59, and admitting the pressure medium to the cylinder 56 which operates the pivoted arm 51. Thereby a pair of flasks are automatically deposited onto the casting machine.

70 At this point the operator manually moves the master control lever 100 causing the pressure medium to be admitted to the pressure cylinder 23, the plunger 24 of which then causes the advancement, through one space, of each machine in the 75 group of machines on the track 7, one machine of

that group being progressed off the track 7 onto the transfer car 11a. With movement of a casting machine from space A to space B the operating lever 87 of the transfer control valve 78 is swung about its fulcrum 88 causing the transfer 80 control valve 78 to close and the corresponding valve 83 to open. This in turn causes the pressure medium to be admitted to the pressure cylinder 29a and to be cut off from the pressure cylinder 29b. Hence when a casting machine has reached space G the transfer car 11a is at once automatically shifted to space H; and likewise under influence of the counterweight 30b the other transfer car 11b is returned from space A to space N. At about the time of the return of the transfer car 11b to station N the pivoted skid 63 of the mold discharging station has been relieved of the weight of the flask by means of the conveyor 66. The conveyor 66 has by this time operated to carry the flasks toward the stripping station, and hence the pivoted skid is in readiness to receive another pair of flasks.

Incident to the completion of the movement of the transfer car 11a from space G to space H the operating lever 96 of the control valve 95 is moved, 100 causing the pressure medium to be admitted to the control valve 95 operating the pressure cylinder 25. As soon as the transfer car 11a has reached station H the plunger 26 is thus forced outward, causing advancement, through one 105 space, of all of the machines of the group on the track 9. With this movement of the group of machines on the track 9 one machine is advanced onto the transfer car 11b at the mold discharging station 6. Thereupon its flasks are automatically 110 picked up by the pivoted skid 51 engaging the cam surfaces 21 in the manner previously described. The flasks are caused to roll by gravity to a position at the end of the conveyor whereupon the circuit has been completed and the operations are repeated.

From the above description it will be apparent that the apparatus of this invention makes possible an orderly and efficient method of performing the various steps, including the handling 120 steps, involved in making castings by the centrifugal process. It results in rapid production without waste of time and labor. Moreover, it will be understood by those skilled in this art that numerous changes may be made in the particular 125 instrumentalities selected for the practice of the invention, and that certain features of the invention may be used to advantage without a corresponding use of other features, all without departing from the spirit of the invention as defined 130 in the annexed claims.

Having thus described my invention, I claim:

1. In combination with a flask receiving station comprising an elevated support for carrying a flask, and means for raising and lowering said support; a centrifugal casting machine movable to a position beneath said support, said machine including a carriage having bearings for rotatably supporting a flask; and means whereby the movement of said machine to a position beneath said 135 elevated support automatically causes the lowering of the same and the deposit of a flask on the bearings aforesaid.

2. In combination with a flask receiving station comprising a pivoted arm for carrying a flask, 145 and means for raising and lowering said arm about its pivot; a track extending beneath said pivoted arm; a centrifugal casting machine movable on said track, said machine including a carriage having bearings for rotatably supporting 150

- a flask; and means whereby the movement of said machine to a position beneath said pivoted arm automatically causes the lowering of said arm and the deposit of a flask on the bearings 5 aforesaid.
3. In combination with a flask receiving station comprising a pivoted arm for carrying a flask, a cylinder for raising and lowering said arm about its pivot; a track extending beneath said 10 pivoted arm; a centrifugal casting machine movable on said track, and means whereby the movement of said machine to a position beneath said pivoted arm automatically operates said cylinder to effect a lowering of the arm and the deposit 15 of a flask on said machine.
4. In combination with a flask discharging station comprising an elevated skid adapted to be raised and lowered; a centrifugal casting machine including a carriage having bearings for rotatably 20 supporting a flask, and a cam surface adjacent to said bearings, said machine being movable to a position in which said elevated skid extends between the carriage and the flask thereon, and said cam surface being adapted to engage said 25 skid when in that position and to elevate the same, thereby discharging the flask onto said skid.
5. In combination with a flask discharging station comprising a pivoted skid; a track extending to the vicinity of said skid, a centrifugal casting machine including a carriage having bearings for rotatably supporting a flask, and a cam surface on said carriage, said carriage being movable on said track to a position in which a portion 30 of said pivoted skid extends between the carriage and the flask thereon, and said cam surface being adapted to engage said skid when in that position and to elevate the same about its 35 pivot, thereby discharging the flask onto said skid and causing the flask to roll by gravity on 40 said skid.
6. In a foundry plant, a trackway constituting a flask receiving station, an additional trackway constituting a flask discharging station, a set of tracks forming a rectangular closed circuit with 45 portions thereof aligned with the trackways of said flask receiving and flask discharging stations, centrifugal casting machines movable on said tracks, each machine including a carriage having bearings for rotatably supporting a flask and a prime mover for driving the flask; means for progressing said machines around said closed circuit, and means responsive to the movement of said machines for automatically transferring flasks onto and off said bearings at said flask receiving and flask discharging stations respectively. 80
7. In a foundry plant, a trackway constituting a flask receiving station, a parallel trackway constituting a flask discharging station, a set of tracks forming a rectangular closed circuit with opposite sides of said circuit aligned with the trackways of said flask receiving and flask discharging stations, centrifugal casting machines movable on said tracks, each machine including a carriage having bearings for rotatably supporting a flask and a prime mover for driving the flask; means for progressing said machines around said closed circuit, and means for transferring flasks onto and off said bearings at said flask receiving and flask discharging stations respectively. 85
8. In a foundry plant, a series of stations including a flask receiving station, a pouring station and a flask discharging station; a plurality of centrifugal casting machines each comprising a movable carriage having thereon bearings for rotatably supporting a flask, an electric motor for driving the flask, and current collecting means in circuit with said motor projecting from said carriage, means for advancing one such machine 90 from the flask receiving station toward the pouring station while concurrently advancing another such machine from the pouring station toward the flask discharging station, and current supplying conductors in the path of said machines adapted 95 to engage said current collecting means when a carriage is at said pouring station and to disengage said means when a carriage is moved a predetermined distance beyond the pouring station. 100
